CONTAINER OPENING KEY MACHINE

William Pechy, Elizabeth, N. J., assignor to
 American Can Company, New York, N. Y., a
 corporation of New Jersey

Application July 9, 1932, Serial No. 621,674

15 Claims. (Cl. 29—33)

The present invention relates to the manufacture of opening keys such as are used with tearing strip containers and has more particular reference to a fully automatic apparatus for feeding key blanks individually from stack formation into holding elements which subject them consecutively to a series of key forming operations which transform the key blank into a finished key.

10 The principal object of the present invention is the provision of an apparatus having synchronized working elements which operate upon a key blank to convert it into an accurately formed key suitable for an attachment to a container

15 with which it is to be used for removing a tearing strip area in opening the container, certain of these elements removing the key from a magazine and others presenting it to the key forming stations while still other elements restack the

20 finished keys within a second magazine.

An important object of the invention is the provision of an apparatus of the character described wherein a key receiving turret automatically presents the key blank in proper sequence to the operating stations while still retaining it in exact relationship to the turret.

An important object of the invention is the provision of key shank flattening, end forming and bending and key slotting instrumentalities associated in a unit machine having means for holding the key blank accurately in proper register for each of the forming operations.

Numerous other objects of the invention will be apparent as it is better understood from the foregoing description, which, taken in connection with the accompanying drawings, discloses a preferred embodiment thereof.

Referring to the drawings:

Figure 1 is a perspective view of an apparatus embodying the present invention, parts being broken away;

Fig. 2 is a sectional plan view, on a larger scale, of the apparatus disclosed in Fig. 1, this view showing substantially the lower half of the apparatus;

Fig. 3 is a longitudinal sectional view taken substantially along the line 3—3 in Fig. 2;

Fig. 4 is an enlarged transverse sectional view taken substantially along the line 4—4 in Fig. 3;

50 Figs. 5 and 6 are enlarged fragmentary sectional details taken substantially along the line 5—5 in Fig. 2, the two views illustrating different positions of some of the parts;

Fig. 7 is a plan view of the lower part of the key shank flattening and end forming and bend-

ing stations, this view being a fragmentary showing on a larger scale of a portion of Fig. 2;

Fig. 8 is a transverse sectional detail taken substantially along the line 8—8 in Fig. 7;

Fig. 9 is a sectional view, being taken substantially along the broken line 9—9 in Fig. 7 and also showing the upper mechanism at that station;

Fig. 10 is a transverse sectional view taken substantially along the line 10—10 in Fig. 2 or in Fig. 9;

Fig. 11 is a transverse sectional view taken substantially along the line 11—11 in Fig. 10;

Fig. 12 is a sectional view taken substantially along the line 12—12 in Fig. 7, also showing the upper mechanism at that station;

Fig. 13 is a front face detail of the lower part of the mechanism disclosed in Fig. 10, as viewed substantially from a position as indicated by the line 13—13 in that figure;

Fig. 14 is a plan view of a part of the mechanism at the key slotting station; this view being a fragmentary showing on a larger scale of a portion of Fig. 2;

Fig. 15 is a longitudinal sectional view taken substantially along the line 15—15 in Fig. 14;

Fig. 16 is a transverse sectional view taken substantially along the line 16—16 in Fig. 14;

Fig. 17 is a plan view of a part of the mechanism at the key restacking station, this view being a fragmentary showing on a larger scale of a portion of Fig. 2;

Fig. 18 is a front elevation of the parts illustrated in Fig. 17;

Fig. 19 is a transverse sectional view taken substantially along the broken line 19—19 in Fig. 2;

Fig. 29 is a sectional plan view taken substantially along the line 29-29 in Fig. 5;

5 Fig. 30 is a transverse sectional view partly broken away taken through the key blank feeding magazine as indicated by the section line 30-30 in Fig. 5;

Fig. 31 is a plan sectional view taken substantially along the line 31-31 in Fig. 23;

10 Fig. 32 is a transverse sectional view taken substantially along the line 32-32 in Fig. 10; and

15 Figs. 33, 34, 35 and 36 are perspective views of the individual elements associated with the key blanks feeding devices, these elements being shown assembled in Figs. 27 to 30, inclusive, Figs. 33 and 34 being viewed from above and Figs. 35 and 36 showing the under surfaces of the parts.

20 The apparatus disclosed in the drawings for the purpose of exemplifying the invention embodies a turret which is rotated in a step by step movement and which presents key blanks to different operating stations located in spaced positions adjacent to and just outside of the periphery of the turret. This movement of the turret is effected by a form of Geneva wherein a cam having an interrupted groove with disconnected ends is continually rotated beneath the 25 turret, its groove operating upon spaced rollers carried by and beneath the turret.

The shape of this cam groove is such as to rotate the turret through an angular distance equal to the distance between the spaced rollers carried by it and then a straight portion of the 35 groove, operating on the turret roller holds the turret stationary for a rest period. The distance between the ends of the cam groove insures engagement with the next adjacent turret roller as soon as the preceding roller is disengaged at the 40 completion of the rest period. This not only insures a smooth step by step movement but locks the turret during its rest position.

The key blanks in stacked position are 45 contained in a magazine located above and to one side of the turret and the lowermost blank is automatically fed from the bottom of the stack and is moved laterally toward the center of the 50 turret. The blank is then pushed downwardly and its head is moved into one of a series of 55 pockets formed in the turret adjacent its periphery. During the travel of the key blank through the machine and through the operations which follow the head of the blank remains 60 within its turret pocket, its shank projecting out beyond the turret periphery for presentation into the various stations.

The shank of the positioned key blank at the 65 first operating station rests on top of a stationary anvil die and beneath a movable upper flattening die. At this station the head of the key blank is first engaged by a key locating device which positively centers it during cooperation between the movable and stationary die instrumentalities. A flattening of the key shank is 70 the result of the operation at this station.

At a second station the partially flattened key blank is brought to rest upon a stationary die member and directly beneath a movable die. It 75 is again located by engagement with its head and also by a clamping plunger associated with the movable die member. In this held position the end of the shank is further flattened and increased in width while being thinned at its outer extremity. This thinned flattened end of

the key shank is also slightly bent, this producing a key structure which is adapted for attachment to a container by suitable means including soldering or welding. Welding projections are also illustrated as being formed at this station in the flattened end. The particular operations at this station may be varied to suit the conditions for a particular form of key, a key suitable for welding attachment being considered in this instant case as an example.

80 At the third forming station the key blank is brought to rest upon a stationary female die and in alignment with and beneath a movable slotting punch. The head of the key blank is again first centered and its flattened shank is clamped in position. During the following movement of the slotting punch the punch passes through the flattened shank of the key and cuts out a thin wafer of metal, thus providing the desired key slot. This completes the formation of the key.

85 The advancing turret next positions the key into a restacking station. In this position the newly formed key is in alignment beneath a stack of keys supported in a magazine and directly above a discharge head which operates during the rest period of the turret to lift the key out of its turret pocket and insert it within holding fingers in the restacking magazine and at the bottom of the stack of keys.

90 A conventional type of arch press is illustrated in the drawings as the principal supporting frame for the various operating parts of the apparatus. This press comprises an arch head 51 (Fig. 1) connecting with vertical columns 52 which are an integral part of a bed 53 which joins the columns at their lower ends. This part of the press frame rests upon a frame 54 formed with supporting legs 55 which stand upon a base 56. The arch section 51 of the apparatus is 100 formed with bearings 61 which rotatably support a crankshaft 62.

105 An electric motor drive is illustrated as one form of driving power for the shaft 62 and for this purpose a belt pulley 63 is mounted upon the shaft. A belt 64 operates over the pulley 63 and over a small pulley 65 secured to a horizontal shaft 66. This shaft 66 is journaled in a bearing 67 formed in the frame 54 and in a second bearing 68 formed in a bracket 69 mounted upon the base 56.

110 The shaft 66 carries a spur gear 75 which meshes with a pinion 76 secured to a motor shaft 77 of an electric motor 78 located upon the base 56 inside of the frame 54. By means of this connection, rotating power is applied to the crankshaft 62 to effect continuous rotation during the 115 operations of the machine. A turret 81 is mounted above the bed 53 and in front and centrally of the columns 52. This turret rotates in a horizontal plane in a step by step movement and provides the means for conveying the key blanks through the apparatus. The outer rim section of the turret in one complete rotation passes through five different stations located in angularly spaced positions adjacent its periphery.

120 The first station is a key blank feeding station, then follow in sequence three key shaping or forming stations and the last station is a 125 finished key restacking station.

130 With this brief description of the general features of the apparatus, further detailed consideration will now be given to its various parts. Such a description, for purposes of clearness and simplicity, will follow roughly a classification of the details into groups according to the opera- 135

145

150

tions performed upon the key blank or the resulting key. The key blank feeding station parts will now be considered.

Key blanks 91 (Figs. 2, 5 and 6) are arranged 5 in stacked formation within a magazine 92 comprising a vertically extending frame 93 provided with a slot 94 in which the key blank heads (designated by the numeral 95) rest. Angle plates 96 are secured to the front of the frame 93 and 10 extend partially across the slot 94. The inner edges of these plates are spaced away from each other and leave a slot 97 in which the key blank shanks (designated by the numeral 98) rest.

The magazine frame 93 (Figs. 2, 3 and 5) is 15 extended laterally at its base in a lower section 101 secured by bolts 104 to a magazine body frame 105 (shown in detail in Fig. 35). The parts 101, 105 may be connected in a tongue and groove joint 106 (Figs. 6 and 29) to insure exact registration. The body frame 105 is mounted upon 20 and carried by a casing 111 which is in turn carried by the press bed 53. Bolts 112 passing through lugs 113 formed in the frame 105 provide for the necessary attachment of it to the 25 casing.

The magazine body frame 105 is recessed or 30 cut back from its under surface as at 114 (Figs. 27, 30 and 35) and this forms a pocket for a block 115 (Fig. 36) which is seated in the recess 35 and which is secured by bolts 116 to the body frame, the lower face of the block being flush with the lower face of the frame. The frame is slotted longitudinally at 117, this slot extending across the entire length of the frame in a horizontal plane directly above the block 115. Sections 40 of the walls of the slot 117, midway of the frame and directly opposite each other, are cut back and form vertical slots 119. The slots 119 provide pockets for a stationary block insert 121 (Figs. 27, 29 and 33) which rests upon the block 115.

The uppermost surface of the block 121 is flush 45 with the upper surface of the magazine body frame 105. Block 121 in its top face is centrally slotted at 123 and a projecting ledge 124 formed on the bottom of the magazine frame 93 extends downwardly into the slot 123 and holds the parts in register (Fig. 30).

The block insert 121 is vertically apertured at 50 125 and this opening communicates with the slot 94 of the magazine, providing free and unrestricted passage for the heads 95 of the key blanks 91. A connecting vertical slot 126 is also cut through the insert for the shanks 98 of the 55 key blanks.

The lowermost key blank within the magazine is cut out and slid horizontally by a separating and feeding device comprising a slide 134 (Figs. 5, 27, 30 and 34) which moves in the slot 117 60 and rests upon the block 115. The slide 134 also moves through the insert block 121 and in a groove 135 cut along its lower face. The groove 135 is the same width as the groove 117 and the insert block 121 forms a bridge over the slide.

The slide 134 is centrally cut away in a longitudinal slot formed with a wide section 136 (Figs. 27 and 34) adjacent one end of the slide and a narrower section 137 at the other end. The side walls of the slot sections are joined by 70 curved connecting walls 138 shaped to correspond to parts of the rounded key blank heads 95. The slide 134 is adapted to be moved to one position where the walls 133 register with one edge wall of the opening 125 in the block insert 121 and 75 into another position where these walls 138 reg-

ister with the edge wall of an opening 139 (Fig. 36) cut through the block 115.

A groove 141 is cut in the upper surface of the slide 134 and extends from one end of the slide to a point adjacent the opposite end of the slot 137. This groove is of a depth slightly in excess of the thickness of a key blank 91 and provides supporting shelves 142 on opposite sides of the slot sections 136, 137.

In the position of the slide as illustrated in 80 Figs. 5, 27 and 30 the stack of keys in the magazine rests upon the shelves 142, the head of the lowermost key directly engaging the shelf surfaces. The block 115 is formed with a pair of projections 143 which extend upwardly from its upper surface and into the slot section 137 of the slide 134. The shank 98 of the lowermost key blank 91 in the magazine rests between these projections 143, as shown in Figs. 27 and 29. This prevents turning of the lowermost key 95 blank.

The removal of a key blank from the magazine is effected by movement of the slide 134 first toward the left (as viewed in Figs. 5 and 27) to engage the key blank and then toward 100 the right to remove it. In the first movement the rounded walls 138 are brought into register with the side of the slot 125 and with the lowermost key blank 91 in the magazine. This position is shown in Fig. 6. When so registered 105 the lowermost key drops into the slot sections 136, 137 and upon the upper surface of the block 115. The entire stack of key blanks is lowered the same distance at this time.

With the return movement of the slide which 110 immediately takes place (toward the right) and into the position shown in Fig. 5, the lowermost key is slid over the block 115 and is brought to rest with its head against a stop 144 (Figs. 27 and 36) projecting upwardly from the surface 115 of the block 115 just back of the slot 139. The stop 144 extends into the wide slot section 136 of the slide 134.

To regulate the sliding movement of the slide member 134 one end is formed with a transverse 120 slot 146 (Figs. 5, 6, 27 and 28) cut out in its under surface and a pin 147, having a square head 148, operates within the slot 146 and provides a loose connection for a cam control. Pin 147 is carried in a boss 149 formed in an arm 125 151 (see also Figs. 2, 3 and 19) of a lever 152 mounted for oscillation upon a stud 153 threadedly secured to the frame 111.

An arm 161 of the lever 152, opposite to the arm 151, is pivotally connected at 162 to a block 130 163 threadedly secured to a rod 164 extending into a tubular spring housing 165 which is pivoted at 166 on a bracket 167 projected from and secured to a gear casing 168. This gear casing extends along one side of the press frame and 135 is bolted at 169 to the frame 111.

The rod 164 extends loosely through a block 175 threaded in the unpivoted or free end of the spring housing 165. A collar 176 is pinned to the end of the rod and a compression spring 140 177 is located in the spring housing, surrounding the rod, and is confined between the collar 176 and the block 175. This spring tends to pull the rod 164 into the housing 165 and to move the lever 152 on the stud 153. When such 145 movement takes place the slide 134 is moving the key away from the magazine as has just been described.

The slide 134 is moved on its initial or key register stroke, (toward the left, Figs. 5 and 150

27) against the action of the spring 177 by a cam control which will now be explained (see Figs. 2, 3, 5 and 19). A hub 181 is loosely mounted on the stud 153 directly beneath the lever 152 and carries a projection 182 extending rearwardly beneath the arm 161 of the lever.

10 A stop screw 183 is carried in the projection 182 and normally engages a downwardly extending lug 184 formed as an integral part of the arm 161. Adjustment of the screw within its threaded seat determines the relative position between the sleeve 181 and the lever 152. The spring 177 holds the stop screw against its seat under normal key blank feeding conditions 15 during which time the lever 152 and sleeve 181 move as a unit. The sleeve 181 is integral with on arm 185 which extends on the side opposite to the projection 182. Arm 185 carries a pin 186 on which is rotatably mounted a cam roller 187 which operates within a groove 188 of a cam 20 189 keyed to a horizontal cam shaft 191. This constitutes the active element of the cam control referred to.

25 The key blank is separated from the magazine when the cam groove 188 of the cam 189 causes a movement of the parts 182, 185. The screw 183 then tends to back off from the lug 184 of the lever arm 161 but the spring 177 holds the lug against the end of the screw and causes a corresponding movement of the lever arms 151, 30 161 as the lug follows the cam moved screw. The full stroke of the cam, therefore, normally allows for a complete movement of the arms 161 and 151 and the slide 134 moves through its 35 stroke sliding a key blank from the magazine.

40 Should there be an impedance to movement of the slide such as a jammed or improperly positioned key blank, the spring 177 will take up the movement of the lever 181 and the slide will remain stationary without damaging the parts of the apparatus.

45 The cam shaft 191 (Fig. 3) is journaled in a bearing 201 formed in the frame 111, in a bearing 202 formed in a flanged bushing which is secured by bolts 203 to the frame 111 and also in a bearing 204 formed in the gear housing 168. The cam shaft 191 is driven through a chain and sprocket connection with the crankshaft 62 and 50 of the connections to prevent jamming in the event of abnormal operating conditions affecting the cam shaft.

55 For this purpose the shaft carries a clutch disc 211 which is keyed in position and which carries one or more clutch balls 212 which may be backed up by a cam disc 213 mounted upon and keyed to the hub of the disc 211. These parts constitute the stationary elements of the slip clutch. A sprocket 214 is loosely mounted upon the shaft 60 191 so that under certain conditions it may have sliding, as well as rotating, movement relative to the shaft.

65 One face of this sprocket is adjacent to one face of the disc 211 and one or more depressions or pockets 215 are formed in the face of the sprocket. Each pocket is adapted to normally contain its clutch ball 212. As long as the ball 70 212 is seated within the pocket 215, the sprocket and disc rotate as a unit and the shaft 191 is driven at the same rotative speed as the sprocket. The sprocket 214 provides the movable element of the slip clutch and is normally held in clutched position by a spring 216 which surrounds the shaft 191 and a hub 217 of the sprocket.

75 One end of the spring 216 engages a ball bear-

ing unit 218 mounted upon the sprocket and the opposite end of the spring is held on a collar 221 threadedly disposed upon the shaft 191. A locknut 222 is also threaded on the shaft and provides a holding element for the collar after it has been moved into adjusted position. This adjustment of the collar 221 controls the compression upon the spring 216 which in turn provides a definite resistance for the slip clutch.

80

85 In the event of improper operating conditions which hold the shaft 191 from normal rotation, the resistance of the spring 216 is overcome and the sprocket 214 moves back sufficiently to allow its ball seat 215 to disengage the clutch ball 212 and the sprocket 214 moves idly on the shaft. 90 Upon removal of the obstruction and the resuming of normal operating conditions the ball or balls snap again into their proper pockets and again move in proper time with the sprocket, this being also in proper time with all of the working parts of the apparatus.

95

95 The sprocket 214 receives its driving connection from the crankshaft 62 by means of a chain 225 (Figs. 1, 3 and 19) which operates over the sprocket and also over an idler sprocket 226 rotatably mounted on a shaft 227 carried in a bracket 228 bolted at 229 to a part of the gear casing 168. The chain 225 also passes over a second idler sprocket 231 which is rotatably mounted on a stud 232 clamped in fixed position 105 within a slot 233 formed in a boss 234 carried upon an extension 235 of the bracket 228. This stud 232 is preferably adjustable within the slot 233 and such adjustment is utilized for tightening the chain 225. The chain 225 at its upper end 110 operates over a sprocket 236 (Fig. 1) which is carried on the crankshaft 62.

100 When a key blank 91 has been moved into its separated position (the right hand lower key in Figs. 5 and 27) its head is directly over the slot 115 139 and above a pocket of the turret 81 and directly beneath a vertically moving device which operates to move the key blank downwardly from its position and into the turret. The shank of the key is now in alignment with a slot 249 (Figs. 120 30 and 36) which joins the slot 139 and which is also cut through the block 115. The turret and its associated mechanism will now be described.

115 The turret unit comprises a turret ring 251 (Figs. 2, 4 and 5). This ring is mounted upon 125 a turret body 252 which is provided with a hub 253 rotatably mounted on a shouldered stud 254 located within a vertical bore 255 formed in the frame 111. A locknut 256 threadedly secured to the end of the bolt clamps it solidly in fixed position in the frame. The stud 254 (see also Fig. 26) at its top is just above the upper surface of the hub 253 and washers 257 are located upon the upper end of the stud 254 and extend over the end of the hub.

135

130 These washers are held in position by a shouldered bushing 258 which is set into a vertical bore 259 formed in the upper end of the stud 254. A bolt 260 is threadedly engaged within the upper end of the stud, its head resting upon the bushing 258 and holding it in place so that the washers 257 prevent vertical displacement of the turret body while permitting free rotation on the stud.

140 The turret ring 251 is secured to the turret body 145 252 by bolts 261 (Figs. 2 and 4) and a pair of locating keys 262 may also be used to provide easy and accurate assembly. Each key 262 is rounded at its inner end and fits within a pocket 263 formed in the hub 253 of the turret body and the keys 150

are held in position by screws 264 threadedly engaging the turret body. The outer end of each key 262 extends into a pocket 265 cut in the turret ring.

- 5 An annular groove 271 is formed in the upper surface of the turret ring 251 adjacent its outer periphery and pockets 272 are cut into the body of the ring at spaced intervals along the groove. Each pocket is substantially the shape and size 80 of the head of a key blank and a radial slot 273 also formed in the ring and communicating with the pocket is of a size to accommodate a section of the shank 98 of the key blank.
- 10 of the head of a key blank and a radial slot 273 also formed in the ring and communicating with the pocket is of a size to accommodate a section 85 of the shank 98 of the key blank.

One of the pockets 272 is directly beneath and 15 in alignment with the head of the separated key blank when the slide 134 brings it into position as previously described. The movement of the turret and the mechanism for aligning and holding its pocket into key blank receiving position will 90 now be considered.

The turret is rotated on the stud 254 in a step by step movement through a given arc of travel and is then brought to rest for a time interval which is sufficient for the mechanism at the 25 various operating stations to perform their several 95 functions upon the key blank.

A plurality of shouldered studs 281 are held in vertical position within the turret body 252 by nuts 282. There are the same number of studs 30 281 as there are turret pockets and each stud bears a definite relation as to position with its associated key pocket. The turret ring 251 is recessed at 283 for access to each nut 282. A tapered cam roller 285 (Figs. 3 and 4) is carried upon the lower end of each stud 281 and is adapted to be engaged by a barrel cam 286 feathered and mounted upon the shaft 191.

A pair of adjusting collars 287 are threadedly 40 engaged upon the shaft 191 on opposite sides of the cam 286 and provide longitudinal adjustment for the cam. This accurate adjustment of the cam insures correct positioning of each turret pocket 272. Cam 286 is provided with an interrupted groove 288 which, during rotation of the 45 cam with the cam shaft, engages at one end with one of the cam rollers 285 a part of the groove being so shaped as to move the cam roller through a given arc and effect a corresponding step rotation of the turret upon its axis.

50 A portion of the interrupted groove 288 is formed at right angles to the axis of rotation and when this part of the groove engages the roller the latter is held against movement and the turret is then on its rest period. As soon as the cam 55 groove has been carried around for a complete rotation so that the end of the groove leaves the roller 285, its opposite end engages the next adjacent roller on which it then operates in like manner for a moving and a rest period. In this 60 way each complete rotation of the cam effects a movement and rest period of the turret which corresponds to one cycle of operation for the other various parts of the apparatus.

The device for moving the separated key blank 65 into the aligned turret pocket 272 is best shown in Figs. 2, 3, 4 and 5. A cover plate 301 is secured by screws 302 to the upright frame 93 on the side opposite to the angle plates 96. This frame 93 is slotted at 303 to provide a slideway for a vertically disposed bar 304 held in sliding position by the cover plate. A ball 305 provides a detent for engagement within a pocket 306 formed in one face of the bar 304 and under the action of a spring 307 confined within a hollow plug 308 tends 75 to register the bar in its normal raised position,

this being the position of the parts during the separation of the key blank from the magazine. The plug 308 is screwed into the cover plate.

The upper end of the bar 304 is formed with spaced horizontal walls 311 which engage opposite sides of a rod 312 carried in the free end of an arm 313 secured to a horizontal rockshaft 314 journaled for oscillation in a bracket 315 bolted at 316 to one of the column members 52. Oscillation of the shaft 314 and the arm 313 imparts vertical movement to the bar 304. 85

The lowering of the bar 304 for the key blank positioning operation is performed by a compression spring and is controlled by a cam. In other words the bar is positively raised under cam action and is yieldingly lowered under spring action. This prevents jamming of the parts in the event of improper positioning of the key prior to feeding into a turret pocket. A lever 321 is clamped upon the opposite end of the shaft 314 (see also Fig. 19) and the boss of this lever is split at 322. It is tightly clamped to the end of the shaft by a bolt 323. 95

The lever 321 has two arms 324 and 325, the former being associated with the compression spring referred to and the latter being under direct control of the cam. The arm 324 is pivotally connected at 331 with a block 332 threadedly engaging the end of a rod 333 which extends into and has sliding movement within a spring 100 barrel 334.

The rod 333 is formed with a hollow head 335 where it extends within the spring barrel and a coil spring 336 is located in this hollow chamber being interposed between the end of the head 110 and the end of the spring barrel. The spring barrel 334 is pivoted at its lower end to a stud 337 projected outwardly from a boss 338 formed in one of the press frame columns 52 (see Figs. 2 and 19). A plug 339 is threaded engaged in 115 the end of the spring barrel 334 and retains the parts in position.

The spring 336 tends to lift the rod 333 and arm 324, and through the shaft 314 and arm 313 to lower the bar 304 for a feeding operation. 120 This action of the spring is resisted and such movement of the parts is prevented except at each key blank positioning operation. For this purpose the arm 325 carries a pin 341 on which is rotatably mounted a cam roller 342. The roller 342 engages the peripheral cam face of the cam disc 213.

The lower end of the bar 304 (Figs. 5, 6 and 29) is formed with a foot 345 which is elongated in cross section at 346 adjacent grooves 347 130 formed in its side walls. The slot 126 of the block 121 is enlarged as at 348 (Fig. 33) and the bounding walls of the slot are shaped to allow clearance for the bar foot when it is lowered through the block. The section 346 of the bar 135 304 engages the head of the key blank as it rests against the projection 144 and other parts of the foot engage the shank of the key.

The bar 304 forces the key blank from the position shown in Fig. 5 and from the slot sections 140 136, 137 of the feed slide 134, through the slots 139, 249 of the block 115 and deposits it into the aligned turret pocket 272 beneath. This key seated position is shown in Fig. 6.

The width of the slot 249 is practically the 145 same as the diameter of the key shank 98 and requires a positive forcing action (by the bar 304) to move it through the slot. It is because of this feature that the key blank does not fall through the slots 139, 249 when it is deposited 150

above them by the slide 134. This close fit is utilized for another purpose which is to permit the block 115 to act as a stripper and to prevent lifting of the key from its turret pocket when 5 the bar 304 returns to its raised position.

The cover plate 301 is extended laterally at 10 351 to provide a support for a setscrew 352 which is held in adjusted position by a locknut 353. The upper end of the screw 352 forms a limit stop for the downward movement of the bar 304 under the action of the spring 336, the lower 15 wall 311 of the bar top striking the screw at the end of the blank positioning stroke.

The key blank 91 within the turret pocket 272 begins its travel through the apparatus upon 15 the next step rotation of the turret. There are two idle stations at which the key comes to rest and at which no work is done before it reaches the first operating station. During this travel 20 and throughout the travel of the key blank with the turret, its shank extends beyond the periphery of the turret and slides over a circular section 355 (Figs. 2 and 7) of the frame 111.

When the key comes to rest in the first or key 25 flattening station, this position being centralized along the section line 12—12 in Fig. 7, its extending shank 98 is diametrically disposed over the upper surface of a cylindrical anvil block 365 (Figs. 7 and 12). This block is grooved at 366 30 for locating purposes, a bolt 367 being used to lock within the slot and hold the anvil block in located position. The anvil block 365 rests within a counterbore 368 formed in a die shoe 369 secured to the bed 53 of the apparatus. A bolt 371 threadedly engaging within the bottom of the anvil block holds it in fixed position within the die shoe. 35

The die shoe 369 is located in a definite position upon the bed 53 by means of a transverse key 372 (Fig. 9). This die shoe not only forms a 40 support for the stationary die parts of the first flattening station but also for the stationary die parts for the second station. A similar die shoe is also used at the third or key slotting station and this is also mounted upon the bed 53. The 45 die shoes of the respective stations are wedge-clamped, as well as bolted and keyed in fixed position.

The die shoe 369 is held on the bed 53 by a bolt 373 and by the clamping wedge device referred to which forces the die shoe against the key 372. This clamping device includes a wedge shaped head 374 (Figs. 7, 9 and 16) formed on the upper end of a bolt 375 which extends through a section of the bed and is held by a lock nut 376. 50

One of the tapered faces of the head 374 engages an angular notch formed in a member inserted in the die shoe 369 at the second station and the opposite inclined face of the head similarly engages an angular notch of a second member inserted in the second die shoe at the third station. Both of these clamping engagements will be described in detail hereinafter. At present the first or key flattening station will be considered and the anvil block 365 constitutes the stationary die member of the flattening die at 60 this station.

The movable die parts are carried in a press slide 381 (Fig. 1) which is mounted for sliding movement within the column sections 52 and this 70 press slide is moved up and down by connection with the crank shaft 62, the usual form of pitman 382 connecting with a crank 383 formed in the crank shaft 62 being used for this purpose. A movable slide head 384 (Figs. 9 and 12) is secured 75 to the press slide in any suitable manner and a

movable die holder 385 is clamped to the slide head. One form of clamp is illustrated (Fig. 9) and comprises a clamping plate 386 bolted to the side of the slide head and formed with an inclined surface. The die holder may be formed 80 with a flared head 387, one side of which is seated in an inclined wall pocket formed in the slide head, the other side being engaged by the inclined face of the clamping plate 386.

A key holding device is used for insuring proper retension of the key within its turret pocket during the flattening operation. For this purpose a presser foot 388 is used, being slidably mounted within a vertical bore 389 formed in the die holder 385. This presser foot is shouldered at 390 to limit its downward movement and a coil spring 391 is located within the bore 389 and extends into a vertical recess 392 formed in the upper end of the presser foot. This spring engages the presser foot at its lower end and its top is confined by a threaded plug 393 secured in the die holder 385. 85 90 95

A locating projection 394 extends downwardly from the bottom of the presser foot and as the press slide and movable die parts are lowered, this projection passes into the opening in the head of the key blank 91. The lower face of the presser foot then comes into position on top of the head and holds it in the turret pocket as the spring 391 yields to permit the full downward stroke of the press slide. The active movable die elements at this flattening station comprise a die member 395 inserted within the lower end of the die holder 385 and held in clamped position by a bolt 396. 100 105

As the press slide approaches its lowermost position the die 395 presses into the shank 98 of the key blank and flattens a portion of the shank as shown in Figs. 7 and 12. When the press slide 381 is raised following the flattening operation just described, the spring 392 expands and holds the presser foot 388 in key blank holding position until after the die member 395 has fully cleared the key blank. The presser foot thus acts as a stripper to prevent dislodgement of the key from the turret pocket. 110 115 120

The next step rotation of the turret positions the flattened key blank at the second or end flattening and bending station. At this station the end of the key shank is subjected to a flattening operation which may take on one of several variations. In the event that the key is to be subsequently secured to a container in a welded joint the forming of projections on the lower surface of the flattened end part may be desirable as well as a further bending of the flattened end. The drawings illustrate a typical die for 125 130 135 performing a combined bending, end flattening and projection forming operation for making a key suitable for welding.

An anvil block 401 (Figs. 7, 10 and 11) is inserted within the die shoe 369 at a position beneath the key blank shank as it is held by the turret at this station. Bolts 402, 403 passing through the anvil block threadedly engage the die shoe and hold the block firmly in position. It is this anvil block that is engaged by one of the tapered faces of the wedge clamp head, the anvil block having an angular notch 404 for this purpose. The die shoe 369 is thus held in place through the medium of the anvil block 401. 140 145 150

A die holder 405 is adjustably located within a slot 406 extending across one end of the die shoe. The upper outer walls of the die holder are tapered at 407 to provide for holding it in place. A clamping plate 408 is inserted within 150

- a recess 409 formed in the die shoe 369 adjacent to the slot 406 and one side of the plate engages one of the upper tapered walls 407 of the die holder. 80
- 5 The opposite tapered wall is engaged by a similar tapered wall 411 formed in the die shoe. This formation of tapered surfaces allows for longitudinal adjusting movement of the die holder 405 and prevents upward displacement. When 10 the die holder is adjusted for position it is clamped by the plate 408, screws 412 for this purpose extending through the plate and threadedly engaging the die shoe. 85
- This mounting of the die holder 405 permits of 15 its accurate positioning for the proper key flattening and bending operation. To provide a micrometer adjustment there is further provided a bolt 415 which is threadedly engaged in a bracket 416 (see also Fig. 13) secured by cap screws 417 to the die shoe 369. The outer end of the shank of the bolt 415 is formed with a flattened end 418 on which a wrench may be applied for turning the bolt. 90
- The opposite end of the bolt is formed with 20 an enlarged head 419 which extends into a transverse slot 421 cut in the under surface of the die holder 405. A locknut 422 threadedly engaging the bolt 415 is adapted to clamp against the bracket 416 and hold the bolt in adjusted position. 95
- 25 The die holder 405 is vertically recessed at 425 to accommodate a lower die 426. In its inserted position the die 426 rests upon the upper surface of the anvil block 401 and constitutes the stationary die element at this station. 100
- 30 The upper or movable die parts are carried by the slide head 384 (Figs. 4, 9, 10 and 32). A key locating and holding device is also carried by the slide head and this comprises a block 431 which is bolted to the under surface of the slide head adjacent the die holder 385 being held in position by bolts 432. A plate 433 is or may be inserted between the block and the slide head to form a backing for certain parts of the key holding device. 105
- 35 The block 431 is provided with two vertically extending slots 434, 435 and a transverse slot 436 just beneath the plate 433. A key locating plunger 441 is slideably mounted in the slot 434 and is held in sliding position by a plate 442 secured by screws 443 to the block 431. This plunger is formed with an upper projection 444 which extends into a slot 445 formed in the plate 442 in register with the transverse slot 436 and forms a stop limiting the downward position of the plunger. The plunger is hollow and a spring 446 is located in its upper section, the upper end of the spring resting against the plate 433. The plunger 441 at its bottom end carries a projection 447 adapted to partially enter and hold down the head of the key blank 91 in the turret pocket beneath. 110
- 40 A key holding presser foot 451 is also provided and is slidably mounted within the slot 435, being held in position by a plate 452 secured by bolts 453 (Fig. 32) to the block 431. This presser foot is provided with an upper projection 455 (Fig. 10) which extends into a slot 456 formed in the plate 452, in register with the transverse slot 436 of the block 431. This upper projection of the presser foot limits its downward movement of 115
- 45 the plunger within its seat. The presser foot 451 is hollow at its upper end and a spring 457 located in the recess has its upper end engaging the plate 433. The lower end of the presser foot 50 is adapted to engage and hold the shank of the 120
- 50 key as its head rests in the turret pocket at this station. 125
- The slide head 384 also carries a movable die element for cooperation with the die 426. This movable die element comprises a tapered or conical walled disc die 471 (Figs. 10 and 11) which is mounted upon a horizontally disposed bolt 472 having a head which rests within a counterbore formed in the die. The bolt 472 is carried in a bracket 473 secured by bolts 474 to the under surface of the slide head 384. Bracket 473 is formed with a circular seat 475 in which the disc die 471 is partially engaged, this seat forming a backing-up surface for the die. 130
- The die 471 has several operating faces, only one of which, the bottom face, is used at a time. A locating pin 476 is inserted in the disc die 471 and in the bracket 473 and functions as a locating pin to center the former in operating position. The circular die member 471 is provided with a series of recesses 477 and it is into one of these recesses that the end of the pin 476 engages when the die member has been turned on its bolt 472 to present the desired surface at the bottom. This construction of the die allows for a renewal of its wearing surface when needed. A washer 481 is located upon and locknuts 482 threadedly engage, the outer end of the bolt and hold it and the disc die in clamped position. 135
- 55 When the press slide 381 descends the key located plunger 441 first comes into action and part of its lower end 447 enters the head of the key as it rests within the turret pocket, other parts yieldingly engaging the key blank head as the spring 446 is compressed. 140
- 60 Immediately following the presser foot 451 engages the flattened shank of the key blank. The lower end of the presser foot is forked at 485 (Fig. 32) and the legs of the fork straddle the shank of the key blank and center it upon the lower die 426 as the spring 457 yields. The die holder 405 is recessed on opposite sides of its upper face at 486 to form pockets for the fork ends 485. When thus clamped by both yielding members 441, 451 and still during the downward movement of the press slide, the key blank is engaged by the descending die 471 which presses it against the upper surface of the die 426. 145
- 65 The inclined lower surface of the upper die disc cooperating with a similar inclined surface of the upper end of the die 426 bends the end of the key blank at the same time flattening it to the desired shape as illustrated in the middle key blank in Fig. 7. If projections are to be formed in the end of the key, this being illustrated in the drawings, the face of the die 426 is properly recessed for this purpose. 150
- 70 This completes the operation at this station and to allow for the unobstructed passage of the bent end of the key blank from its position between the die parts 426, 471 a channel 491 (Figs. 7 and 11) is cut in the upper surface of the die shoe 369. 155
- 75 The slotting of the key blank is performed at a third operating station. The key, its head resting in the aligned turret pocket, comes into a position above a lower die block or holder 501 (Figs. 14, 15 and 16). Both of the stationary and movable die elements at this station are mounted upon and carried by the bed 53. 160
- 80 The die shoe for this station is formed as a bracket 502 which is positioned upon the bed between the press columns 52 and is held on one side by bolts 503 threadedly engaging in the bed. The die block 501 is inserted in the bracket from 165

below and is clamped down on the bed 53 by the wedge block head 374. The tapered surface of the head opposite to that engaging the notch in the anvil block 401 engages a similar notch 507 formed in the holder 501. It will now be seen how this wedge block 374 performs the dual function of holding the two die supporting members 369, 502 of the two previously described stations and of the present station.

10 The die block 501 is secured to the bracket 502 by bolts 508 and is centrally apertured at 509 to communicate with a vertical opening 514 formed in a lower or stationary die member 515 which is mounted upon the die block 501 and

15 which is held in position by bolts 516 (Fig. 16) extending through the die block 501 and threadedly engaging the die member 515. This die 515 constitutes the female element of the slitting dies.

20 The upper movable or male die elements for slitting the flattened shank of the key are mounted for vertical movement within the bracket 502, which has an upwardly extending cylindrical body 521 (Figs. 14, 15 and 16). The body 521 is provided with a vertical bore 522 in which not only the male die elements are disposed but also certain registering and holding devices.

25 A sleeve 523 has vertical movement within the body 521 and is provided with a featherway 524 which extends along one side. A feather 525 is secured by a bolt 526 to the body being located in a recess therein and one end of the feather extends into the featherway. This prevents turning of the sleeve and maintains its alignment at all times.

30 A key holding tubular shell 527 is inserted in the lower end of the sleeve 523 and is united with the sleeve by screws 528 as shown in Fig. 16. This shell 527 is formed with a center bottom boss 529 which is adapted to engage and holding the shank of the key blank during the slotting operation. The bottom of the shell is also extended on one side in a wall part 531 (Fig. 15) which slides in a slot 532 (see also Fig. 14) cut in the bracket body 521, this construction preventing rotation of the parts 523, 527 in the bracket body.

35 A stem 535 is mounted inside of the shell 527 and sleeve 523 and has some sliding vertical movement. This stem is formed with an annular flange 536 adjacent its upper end which engages an annular shoulder 537 formed in the top of the sleeve 523 when these parts are in a raised position. The upper end of the stem 535 is slotted at 538 (Figs. 1, 3 and 15), this slot extending through one side wall and communicating with a vertical bore 539. A second lateral slot 541 is also cut through the stem wall adjacent the slot 538.

40 The slots 538, 541 are adapted to receive a bolt 545 which normally supports the movable die elements at this station. The bolt is inserted from the front of the apparatus and its head is seated in the slot 538, the shank of the bolt being threadedly secured to a ledge 546 projecting outwardly from the slide 381.

45 When the press slide 381 is raised the head of the bolt 545 strikes against the upper wall of the slot 538 and lifts the stem 535. The flange 536 of the latter thereupon engages the shoulder 537 of the sleeve 523 lifting the latter with its shell 527 by sliding the sleeve 523 within the body 521 of the bracket 502. Fig. 1 illustrates this raised position.

50 A spring 551 is positioned inside of the sleeve 523 and surrounds the upper section of the stem 535. One end of the spring engages the flanges

536 and the opposite end presses against the upper edge of the shell 527. When unrestricted this spring holds shell and sleeve so that the flange 536 is in engagement with the shoulder 537.

55 A locating device for centering and holding the head of the key blank as it rests in its turret pocket is brought into play by a lowering of the press slide 381. Such a device comprises a bar 552 (Fig. 15) which is carried, with some vertical play, within a bore 553 formed in the sleeve 523. The lower end of the bar 552 is formed into a presser foot 554 which carries a projection 555 adapted to enter the opening in the head of the key blank as the presser foot is brought into lowered position.

60 The downward stroke of the press slide 381 during a slitting movement and the travel of the sleeve 523 at such time is in excess of the movement of the bar 552 and allows for seating of the presser foot after its projection 555 has entered the opening in the head of the key blank. A spring 556 is located within the bore 553 above the upper end of the bar 552 and provides a yielding holder for the key blank. The bar 552 is transversely slotted at 557 and a pin 558 passes through the sleeve 523 and extends across the slot limiting the amount of vertical play of the bar within its bore.

65 In the same downward movement of the press slide 381 and after the key has been properly located within its turret pocket, the bottom end 529 of the shell 527 engages and holds the flattened shank of the key blank which stops further movement of the shell 527 and sleeve 523.

70 This boss end 529 is formed with two projecting feet 561 (Fig. 16) which straddle the key shank and tend to further center it upon the die 515 prior to the slotting operation. This die part 515 is formed with a pair of spaced vertical holes 562 (see also Fig. 14) which provide a clearance for the feet 561 of the moving shell 527. While the stem 535 continues to move with the descending press slide 381, the spring 551 yields and separation of the flange 536 and shoulder 537 takes place, as illustrated in Fig. 15.

75 During this same downward stroke of the press slide 381 a slotting punch 565 is forced through the shank of the positioned key blank. A split and hollow pin 566 surrounds the punch, being inserted in a bore 567 formed centrally of the stem 535 adjacent its lower end. This pin 566 is enlarged at its bottom end as a foot section 568 which rests in a counterbore 569 formed in the lower end of the stem 535. This foot section also extends laterally on one side at 575 and projects into the lower end of a vertical slot 576 formed in the shell 527. The pin is retained in position on the end of the stem 535 by a screw 577.

80 At the time the bottom end 529 of the shell 527 engages the shank of the positioned key blank, the punch 565 is in a raised position relative to the lower end 529 and its bottom edge is practically in alignment with this lower end surface. This punch 565 is frictionally held in the split pin 566 and to provide the necessary friction to hold it against movement a wall of the pin is engaged by set screws 578 (Fig. 16) threadedly secured in the stem 535 at that position. The heads of these set screws may be reached for manipulation through the slot 576 in the shell 527 and through an aligned slot 579 passing through a wall of the sleeve 523. In this way enough friction is put upon the sides of the punch 565 to hold it in place.

85 The punch 565 is moved to extended position

for the slotting operation and this movement takes place during the time the flange 536 of the stem is moving away from the shoulder 537 of the sleeve, this being at the end of the downward stroke of the press slide. A solid pin 581 is located within a vertical bore 582 formed centrally of the stem 535 and connecting at its lower end with the bore 567. This pin is backed up by a set screw 583 which engages its upper end, this set screw 10 being threadedly secured in a threaded bore 584 formed centrally and adjacent the top of the stem 535.

Adjustment of the screw 583 within the opening 584 determines the position of the pin 581 and the punch blade 565 relative to the stem 535. In the final movement of the punch stem 535 and during the projecting of the punch 565 from the lower end of the part 529 in the slotting operation, the punch cooperates with the die opening 514 of the lower die member 515 and removes a portion of the material of the key blank, forming a slot 585 (Fig. 14). The trim or metal, removed from the key shank in the making of this slot, falls through the opening in the die 515 and 25 through the opening 509 in the anvil block 501 and passes out through the aligned discharge opening through the bed 53.

This completes the slotting operation and completes the transformation of the key blank into a finished key 586 and as the slide 381 returns on its upward stroke the bolt 545 lifts the stem 535. At the first part of this movement the spring 551 holds the shell 527 and sleeve 523 with the bottom end 529 still resting upon the key shank. The punch 565 is withdrawn from the slot 585 and is brought up into a position with its lower face flush or inside of the bottom surface 529. Then further raising of the stem picks up the sleeve 523 and shell 527 as the flange 536 of the former 40 engages the shoulder 537 of the sleeve. At the same time the bar 552 of the key locating device is carried upwardly, the pin 558 then engaging the upper end of the slot 557.

The action just described leaves the slotted key 45 resting on the lower die 515 and upon the next step rotation of the turret the key is swept from this position. From this station the key passes through two idle stations before coming to rest at a stacking station. It is at the stacking station 50 where the key is removed from the turret pocket and again brought into stacked formation within a receiving magazine.

The key at rest in the stacking station is in axial alignment with a receiving magazine formed 55 in a magazine frame 600 (Figs. 17, 18, 23 and 26) which is formed with a foot 601 bolted at 602 to the upper surface of a casing 603. This casing carries all of the magazine parts and is mounted upon an extension 604 formed in the frame 111. 60 The casing and its associated parts are easily removed from this supported position and for this purpose are held in place upon the frame part 604 by a clamping bolt 605 pivoted on a pin 606 held in the frame extension.

65 This bolt 605 swings within a slot 607 formed in the frame part 604 and when in clamping position passes into a slot 611 formed in a boss 612 integrally connected with the casing 603. When in clamped position, this being illustrated in Fig. 70 26, the bolt 605 is located in the slot 611 and a hand nut 613 threadedly engaging the end of the bolt 605 is firmly seated against the upper inclined face of the boss 612. This holds the magazine restacking parts in key receiving position.

75 The casing 603 (Figs. 24, 25, 26 and 31) is re-

cessed from below as at 615 and a block 616 is located within the recess, being held in position by screws 617. The block 616 is slotted at 621 and the finished key 586 resting in the aligned turret pocket is directly beneath this slot. The head is directly beneath the tapered front edge of a fork end 622 (Fig. 26) of a slide plate 623. This plate is mounted in a slot 624 formed in the block 616 at the end of the slot 621. The slide plate 623 is normally held in position to slightly overlap the key head by a pair of springs 625 which are interposed between the outer end of the plate 623 and a block 626 inserted in and secured by screws 627 to the casing 603. This plate is used for guiding the key into stacked position and assists in holding it there as will be hereinafter more fully explained.

In this position the key is also directly above a lifter head 629 (Figs. 23 to 26 incl.) having vertical movement within a pocket 631 located in the frame extension 604. This head has spaced upwardly extending projections 632, 633, the former terminating in a slotted cap 634 which is directly below the flattened bent end of the key. The projection 633 is directly beneath the head 95 of the key and these parts 632, 633 when moved upwardly through the slot 621 engage the key and force it upwardly from the turret seat.

To effect this lift of the head 629, it is secured to the upper end of a sliding bar 641 (Figs. 18, 21, 105 25 and 26) located within a slot 642 cut in the frame 111. A plate 643 is secured to the frame and retains this sliding bar in working position.

The lower end of the bar 641 is formed with an annular groove 644 in which a pair of blocks 645 110 (see also Fig. 20) are located. Each block carries a pivot pin 646 which is mounted in the yoked end 647 of an arm 648 mounted on one end of a sleeve 649 (Figs. 20 and 22) having oscillation within a bearing 651 formed in the frame 115 111. The sleeve 649 is an integral part of an arm 652 which extends upwardly on the outside of the bearing 651.

The arm 652 (Figs. 20 and 22) is clamped in position by a wedge rod 653 which extends 120 through the center of the sleeve 649, one end of the rod being formed with an inclined wall 654 which engages a similar inclined surface 655 formed on a wedge key 656 inserted in a slot 657 projecting laterally through one wall of the 125 sleeve. The arm 648 is also slotted for the wedge key being formed with a keyway 658 for this purpose.

The opposite end of the rod 653 is threaded for the reception of a locknut 659 which clamps 130 against the outer face of the arm 652 and pulls the rod inwardly wedging the key 656 in its seat and holding the arm 648 securely on the sleeve 649. This sleeve is shouldered at 661 and the clamping action just referred to pulls the arm 135 648 tightly against this shoulder. This allows for a free oscillating movement of the sleeve within its bearing.

An arm 665 (also see Figs. 17 and 18) is loosely mounted on the sleeve 649 outside of the bearing 651 and this arm is formed with a lateral projection 666 which extends into a rectangular slot 667 formed in the arm 652. Stop screws 668 are threadedly secured in the arm 652 on opposite sides of the slot and are adapted to engage 145 on opposite sides of the projection 666. By adjustment of the screws 668 the arm 665 is located relative to the arm 652, an accurate adjustment being desirable to raise and lower the bar 641 properly.

The arm 665 carries a pin 671 on which is mounted a cam roller 672 which engages within a groove 673 of a barrel cam 674 mounted upon the end of the cam shaft 191 (see also Fig. 3).

5 A housing 675 surrounds the end of the shaft 191 and encloses the cam 674 and arms 652, 665. This housing may be secured to the frame 111 in any suitable manner.

In the discharge of a key from the turret pocket 10 272 at this restacking station, as the lifter head 629 is raised, the projection 633 passes upwardly through the turret pocket and carries the head of the key 586 with it. At the same time the cap 634 of the projection 632 straddles the flattened 15 end of the key and carries it upwardly. During this movement the key head and then the projection 633 rides against the tapered front edge of the plate 623 and moves it back against the action of the springs 625. The amount of 20 this upward movement is sufficient to carry the key through the slot 621 in the block 616 and into the restacking magazine and where it takes its place at the bottom of the stack of keys within the magazine.

25 During this movement the key passes into a stack retaining device mounted in the magazine, this device comprising a pair of oppositely disposed catch fingers 685 (Figs. 23, 24 and 25). Each finger is pivotally mounted on a pin 686 30 threadedly secured in a block 687 mounted on the face of the magazine frame 600. There are two blocks 687, one on either side of the key and a retaining plate 688 is secured by screws 689 to the face of the block. Each plate is formed with 35 a projection 690 extending downwardly into the slot 621 of the block 616.

These projections 690, located on the sides of the line of travel of the key assist in guiding it into proper stacked position. The magazine 40 frame 600 is vertically grooved at 691 for the reception of the heads of the keys brought into the magazine. Retaining plates 692 secured to the face of the frame 600 retains the stacked keys in position by cooperation with the groove 691 acting on the key heads.

45 When the shank of the key being lifted reached the lower ends of the fingers 685, it engaged inclined hooked ends 695 and spread the fingers by pivoting them outwardly at their lower ends. 50 Such pivotal movement of the fingers takes place against the action of springs 696 interposed between each finger and the adjacent wall of the block 687. As soon as the shank of the key passed beyond the hooked end of the fingers, 55 their springs snapped them back into normal position, the fingers then holding the key just brought into place.

The stack of keys already in the magazine at 60 the time is momentarily raised enmass its entire weight then resting upon the inserted key which is in turn supported by the rising lifter head 629. After the fingers snap in and under the positioned key they then support this weight of the stack of keys. The key stack thus moves 65 upwardly with the addition of each key. When the projection 633 moves down the slide plate 623 moves forward and snaps under the head of the lowermost key, thus assisting the fingers 685 in holding the stack.

70 The magazine frame 600 may be of any suitable height to accommodate a quantity of keys and these keys may be removed from the magazine from above by lifting and sliding them out through the slot 691, this action in no way interfering with the key stacking operation.

When the lifter head 629 has receded into its lowered position the turret is advanced through its regular step movements, its pockets after passing the restacking station being empty and ready for the feeding of key blanks at the blank feeding station. 80

In this way key blanks are automatically fed to the turret, conveyed by the turret through the several key forming and shaping stations and are then automatically removed from the turret, 85 there being no cessation of operations of the apparatus, it being only necessary to keep the magazine 92 supplied with key blanks and to remove the finished keys from the restacking magazine.

It is thought that the invention and many of 90 its attendant advantages will be understood from the foregoing description and it will be apparent that various changes may be made in the form, construction and arrangement of the parts, without departing from the spirit and scope of 95 the invention or sacrificing all of its material advantages, the form hereinbefore described being merely a preferred embodiment thereof.

I claim:

1. In a key forming apparatus, the combination 100 of a magazine for holding key blanks in stack formation, a turret having a plurality of pockets mounted adjacent said magazine, means for feeding a single key blank from said magazine and into a said turret pocket, actuating devices for rotating said turret in a step by step movement to successively present a key blank carried thereby to operating stations, die instrumentalities at one of said stations for flattening the shank of said key blank, other die instrumentalities at a second station for shaping and bending the end of said key blank, slotting die instrumentalities at a third station for slotting said blank and completing the formation of a key therefrom, and means for removing finished keys from the turret pockets and placing them in stack formation. 115

2. In a key forming apparatus, the combination 120 of a magazine for holding key blanks in stack formation, a turret having a plurality of pockets mounted adjacent said magazine and arranged to leave a portion of the key held therein exposed beyond the turret, a slide located beneath said magazine and having a key blank receiving pocket, means for moving said slide 125 to position its pocket first into alignment with the stack of key blanks within said magazine to separate the lowermost blank from the stack and then into alignment with a said turret pocket to transfer said separated blank from said magazine into said turret, and actuating devices for rotating said turret to present its key blank to an operating station. 130

3. In a key forming apparatus, the combination 135 of a magazine for holding key blanks in stack formation, a turret having a plurality of pockets mounted adjacent said magazine and arranged to leave a portion of the key held therein exposed beyond the turret, a slide located beneath said magazine and having a key blank receiving pocket, means for moving said slide to position its pocket first into alignment with the stack of key blanks within said magazine to separate the lowermost blank from the stack and then into alignment with a said turret pocket, devices for removing the key blank from the said slide pocket and positioning it into 140 said aligned turret pocket, and actuating devices for rotating said turret to present its key blank to an operating station. 145

4. In a key forming apparatus, the combination of a turret having a plurality of pockets for holding key blanks, said pockets being arranged to leave a portion of the key exposed 5 beyond the turret, an operating station located adjacent said turret, die instrumentalities at said station for shaping a key from a key blank while in said turret pocket, devices for rotating said turret in a step by step movement to present said key blank to said instrumentalities, means for operating said rotating devices, and a safety slip clutch interposed between said rotating devices and said operating means for preventing movement of said turret in the event 10 of abnormal conditions in said apparatus. 5. In a key forming apparatus, the combination of a magazine for holding key blanks in stack formation, a turret having a plurality of pockets mounted adjacent said magazine, means 20 for feeding a single key blank from said magazine and into a said turret pocket, actuating devices for rotating said turret in a step by step movement to successively present a key blank carried thereby to operating stations, and means 25 associated with each operating station for engaging the head of the key blank when presented and for holding the blanks during the key forming operation at that station. 6. In a key forming apparatus, the combination 30 of a magazine for holding key blanks in stack formation, a turret having a plurality of pockets mounted adjacent said magazine, means for feeding a single key blank from said magazine and into a said turret pocket, actuating devices for 35 rotating said turret in a step by step movement to successively present a key blank carried thereby to an operating station, die instrumentalities at said station for performing a key forming operation on said key blank, and 40 adjusting devices located at said station for coordinating said die instrumentalities. 7. In a key forming apparatus, the combination 45 of a magazine for holding key blanks in stack formation, a turret having a plurality of pockets mounted adjacent said magazine, means for feeding a single key blank from said magazine and into a said turret pocket, actuating devices for 50 rotating said turret in a step by step movement to successively present a key blank carried thereby to an operating station, a movable and a stationary die instrumentality at said station for performing a key forming operation on said key blank, and means for moving a said instrumentality to present a new working surface. 55. 8. A key forming apparatus comprising in combination, a turret having a plurality of pockets for holding key blanks, actuating devices for rotating said turret to carry said key blanks to 60 an operating station, slotting die instrumentalities at said station for slotting a key blank when presented by said turret, and yielding devices for holding said key blank in said instrumentalities during said slotting operation. 65 9. A key forming apparatus comprising in combination, a turret having a plurality of pockets for holding key blanks, actuating devices for rotating said turret to carry said key blanks to 70 an operating station, slotting die instrumentalities at said station for slotting a key blank when presented by said turret, yielding devices for holding said key blank in said instrumentalities during said slotting operation. 80 10. A key forming apparatus comprising in combination, a turret having a plurality of pockets for holding key blanks, actuating devices for rotating said turret in a step by step movement to successively present a key blank carried thereby to key forming stations, a restacking magazine associated with said turret, means for removing finished keys from the turret pockets and placing them in stacked formation within said magazine, and fingers located in said magazine 85 for supporting the stacked keys. 11. In a key forming apparatus, the combination of a rotary turret, key forming dies arranged in a series around said turret, and means for engaging a formed head of a key blank to present its stem or shank to said key forming dies, said engaging means being arranged on said turret near its periphery. 12. In a key forming apparatus, the combination of a rotatable turret, means engaging the heads of the keys carried by said turret and arranging the shanks beyond the periphery of the turret, and instrumentalities for performing key forming operations upon the shanks while said keys are so arranged in said turret, said instrumentalities being fixed in series around said turret. 100 13. In a key forming apparatus, the combination of a rotatable turret, means engaging the heads of the keys carried by said turret and arranging the shanks beyond the periphery of the turret, instrumentalities for performing key forming operations upon the shanks while said keys are so arranged in said turret, and a device for engaging the head of a key blank carried 105 in said turret to accurately register the shank of the key blank with respect to said instrumentalities. 110 14. In a key forming apparatus, the combination of a rotatable turret, means engaging the heads of the keys carried by said turret and arranging the shanks beyond the periphery of the turret, instrumentalities for performing key forming operations upon the shanks while said keys are so arranged in said turret, a locating 115 device associated with said instrumentalities for engaging within the heads of the keys and for centering them in said turret-engaging means, and cooperating devices for holding the shanks of the said keys with respect to said instrumentalities. 120 15. In a key forming apparatus, the combination of a rotatable turret, means engaging the heads of the keys carried by said turret and arranging the shanks beyond the periphery of the 125 turret, instrumentalities for performing key forming operations upon the shanks while said keys are so arranged in said turret, devices associated with said instrumentalities for centering and holding the keys in said turret-engaging means, and means associated with said devices for stripping the keys from said instrumentalities 130 after a key forming operation. 135 140

WILLIAM PECHY. 145
